UNITED STATES PATENT OFFICE.

RAYMOND M. INGLES, OF KLAMATH FALLS, OREGON, ASSIGNOR OF ONE-HALF TO
DANIEL WALTERS, OF KLAMATH FALLS, OREGON.

SHOE BRUSH.

Application filed September 18, 1926. Serial No. 136,280.

This invention relates to brushes, and particularly to shoe polishing brushes.

The invention has particular reference to a brush which is driven by an electric motor, 5 and is manipulated by the user, by grasping the handle of the motor and passing the brush over the shoes. In the usual devices of this character, should the operator permit the brush to slip from the shoe, the metal 10 or other casing or head of the brush contacts with the shoe, causing marring scratches, or deep cuts in the leather. It is therefore the principal object of the invention to provide a brush of this type which will not mar the 15 shoe, should the head of the brush contact therewith, such brush being provided with an independently rotatable guard which will contact with the shoe and remain stationary, while the brush continues to rotate.

20 Other objects and advantages will be apparent from the following description when taken in connection with the accompanying drawing.

In the drawing:

25 Figure 1 is an elevation of a shoe polishing brush made in accordance with the present invention.

Figure 2 is a vertical sectional view on the line 2—2 of Figure 1.

30 Referring particularly to the accompanying drawing, 10 represents the head of the brush, which is in the form of a metal disk, within which are secured the bristle tufts 11. From the center of the upper face of the disk 10 there projects a shaft 12, which is adapted to be connected with the shaft of a motor, not shown. The portion of the shaft 12, adjacent the disk 10 is slightly enlarged in diameter and externally threaded, as shown at 13, to receive thereon the nut 14.

40 Engaged on the head 10, is a metal cap 15, having a flange 16 covering the peripheral edge of the head, and a central opening 17 receiving therethrough the threaded portion 13, of the shaft, said opening being of greater diameter than said threaded portion whereby to prevent frictional engagement between the wall of the opening and said threaded portion, while the brush is in operation, 45 thereby preventing the cap rotating with the head. The threaded portion 13 is formed with a transverse threaded socket 18 which receives the locking screw 19, carried by the nut 14, and by means of which said nut is 50 held from backing from the shaft, and also

for holding the nut in such relation to the cap 15 as will prevent the latter from any appreciable rocking movement,—with respect to the head 10, while at the same time permitting free and independent rotation thereof, or inertia thereof against a shoe, while the brush continues to rotate.

From the foregoing it will readily be seen that by the provision of the loosely mounted cap 15, no damage will be done to the face of a shoe, should the operator permit the brush to slip so that the bristles leave the face of the shoe and the cap contact with the shoe. In such an event, the cap would be held stationary by the shoe, while the brush continued to rotate, the head of the brush being thus held from contact with the shoe.

When the brush is at rest the bristles extend longitudinally from the end of the brush head, but when the brush is in rotation, the bristles flex outwardly from the head, laterally, in all directions, whereby to provide a larger bristle surface for action upon a shoe.

What is claimed is:

1. A rotary shoe brush comprising a head having a stem and bristles, a cap loosely mounted on the stem in covering relation to the head and adapted to remain stationary upon contact with a shoe upon which the brush is operating, and means for retaining the cap on the head.

2. A rotary brush comprising a head having a threaded stem, a centrally apertured cap engaged on the stem and loosely embracing said stem and head, and means removably held on the stem in non-contacting relation to the cap, whereby said cap is capable of free rotation on the stem and thereby adapted to remain stationary upon contacting with the object upon which the brush is operating to prevent marring the object.

3. A rotary brush comprising a disk head having bristles extending from one face and a threaded stem extending from the opposite face, a cap embracing said head and having a central opening receiving the said stem and the lower edge of the cap being in the plane of the bristle carrying face of the head, said cap being loose with respect to the stem and head whereby the cap will be frictionally held stationary on contacting with the object being brushed.

In testimony whereof, I affix my signature.
RAYMOND M. INGLES.
